BILL-BOARD AND THE LIKE.

1,216,012.

Specification of Letters Patent. Patented Feb. 13, 1917.

Application filed March 21, 1914. Serial No. 826,241.

To all whom it may concern:

Be it known that we, CHARLES H. TAYLOR and CHARLES F. MELVILLE, residing at New York, county and State of New York, have invented certain new and useful Improvements in Bill-Boards and the like, of which the following is a specification.

This invention relates to a bill board, or the like, structure.

10 A particular object of the invention is to provide a simple, attractive, strong and efficient article of this class, which may be manufactured at comparatively small cost.

15 A further object is to so design the parts that a complete marginal ornamental molding portion may be formed thereon, parts of the molding being formed integrally with the back or base portion of the board.

20 A further object is to so design the structure that separately formed portions of the base, which are integral with portions of the molding, are seamed together in such manner that said seam provides a stiffening rib, preferably centrally of the structure, for 25 strengthening the base.

25 A further object is to provide a structure comprising a base part and an ornamental marginal molding part, and to provide means extending laterally from said molding part whereby the structure may be attached to a wall or the like, and further, to dispose said attaching means in a plane, so that when the base part of the structure is brought into engagement with a wall surface, the subsequent operation of bringing the attaching means into, or near, engagement with the wall surface will serve to dispose the base into forced engagement with said wall surface. The wall will thus constitute a uniform and efficient support for said back in sustaining pressures which may be brought to bear against the said back in use, or by accident.

30 Other objects and aims of the invention, more or less specific than those referred to above, will be in part obvious and in part pointed out in the course of the following description of the elements, combinations, arrangements of parts and applications of 35 principles, constituting the invention; and the scope of protection contemplated will be indicated in the appended claims.

In the accompanying drawings which are to be taken as a part of this specification,

and in which we have shown a merely preferred form of embodiment of the invention:

Figure 1 is the plan view illustrating the several parts of the structure disassembled;

Fig. 2 is a view similar to Fig. 1, but showing the parts in their assembled relation;

Fig. 3 is a vertical, sectional view taken upon the plane of line III—III of Fig. 2; and

Fig. 4 is a view similar to Fig. 3, but being taken at right angles thereto upon the plane of line IV—IV of Fig. 2.

Fig. 5 illustrates a preferred means for attaching the structure to a wall.

Fig. 6 illustrates a slightly modified form of construction.

Fig. 7 is an enlarged sectional view taken upon the plane of line VII—VII of Fig. 6.

Figs. 8, 9 and 10 illustrate further modifications.

In the formation on the device illustrated we provide four separately formed parts indicated in the drawing as 1, 2, 3 and 4. The parts 1 and 2 are the side members, and the parts 3 and 4 are the end members. The parts 1 and 2 are substantially identical, and each comprises a base portion L and a molding portion G. The molding portion of each part is formed integrally from a single piece of sheet metal with the respective base portion, as clearly indicated in Fig. 4 of the drawing. The molding portions are shaped up at the outer edges of the material from which the base portions are formed.

The end members 3 and 4 comprise molding pieces only, they being shaped to correspond to the molding portions G of the members 1 and 2.

The adjacent or inner edges of the portions L are adapted to be seamed together as indicated in Figs. 2 and 4, and this seam obviously serves as a strengthening rib substantially centrally of the base portion.

The opposite ends of the members 1 and 2 are suitably cut for receiving the end members 3 and 4, so that the beveled ends as 5 of said end members will fit to the ends of the molding portions G to complete the structure as shown in Fig. 2. The members 3 and 4 may be soldered or otherwise suitably secured in position.

While it is preferable that the portions L

of the members 1 and 2 be sufficiently wide so that, when combined, they complete the desired width of the bill board, it is, however, obvious that they may be spaced apart in the finished structure, as shown in Figs. 6 and 7 and a separately formed strip 12 be inserted between them for increasing the width of the structure when desired. In this instance, the separately formed strip 10 would, of course, be seamed along its opposite edges to the adjacent edges of the portions L. If more than one such strip is employed for further increasing the width of the structure, all such strips would be seamed together. In the formation of all of these 15 seams, several thicknesses of metal occur, as shown at 6, and each seam, in effect, constitutes a stiffening rib extending across the expanse of the base.

20 The seam or seams may be made to project their increased thickness at both sides of the general plane of the base, as in Fig. 7, but they are preferably arranged to project wholly from the rear surface so that the 25 outer or front surface is level and uninterrupted, as indicated in Fig. 4, as in this way a smooth surface is presented to receive illustrations or any advertising matter which may be pasted or painted upon the outer 30 surface of the base as is customary in the use of bill boards of this class.

In the formation of the molding, said molding is preferably provided with a laterally extending integral flange H continuing 35 from the inner end of its outer leg. This flange may be continuous throughout the length of the moldings as illustrated, in Figs. 1 and 2, or may comprise only ears as 13 in Fig. 6, if preferred. In any event, suitable 40 apertures, as 7, are provided through which the nails, screws or other fastening means, as 8, may be inserted into engagement with the wall for retaining the structure in position.

45 In use, it is desirable, since the structure is formed of relatively thin light sheet metal, and since for this reason the back or base portion of the structure is more or less flexible and susceptible to being bent or 50 dented by accident or otherwise, that this flimsy back portion be disposed as nearly as possible into close engagement with the surface of the wall throughout its extent. In order to insure such engagement between the 55 base and the wall, the flange H is preferably disposed in a plane slightly in front of the plane of the back surface of the base, so that when the fastening means 8 is driven home, the material of the molding will be sprung 60 to a greater or less extent and serve as a resilient means for forcibly retaining the back against the surface of the wall. This is clearly indicated in Figs. 4 and 7 wherein the dotted lines 9 indicate the wall or the 65 plane of the rear surface of the base.

Of course, if desired, the flange H may be made to stand at any level relatively to the rear surface of the base, either in position to space said base away from the wall, as indicated in Fig. 8, or in a plane coincident with the plane of the rear surface of the base as shown in Fig. 3. These relative positions of the flange H may be determined by the thickness of the material employed, or by the nature of the wall to which the device is to be attached.

It is apparent that the nature of the material used in the manufacture of the frame or molding portion of the structure naturally renders said portion resilient, and it is also apparent that, though we have illustrated, and preferably employ, a base portion to the structure, a frame or molding portion formed hollow as illustrated and having one of its edges disposed in a plane in front of the other, as indicated in Figs. 4 and 7, may be constructed and employed without the integrally formed, or attached base portion L. In this instance the lower inner edge of the molding will press resiliently directly against the wall to form a tight joint therewith as in Fig. 9, or directly against a separately formed member, as an advertising card itself or a member to which said advertising card may be attached as in Fig. 10. So far as we are aware, it is new to provide a frame molding formed of resilient material, having its inner edge in a plane behind the plane of its outer edge, and having means at its outer edge whereby the outer edge may be drawn rearwardly toward the plane of the inner edge so as to spring the material of the frame, and thus resiliently force the inner edge into tight contact with the support.

In Fig. 5 we have illustrated a form of fastening means, as 10, particularly adapted for forcing the frame into engagement with the wall. This fastening means is intended to be used principally at the upper end of the structure and is formed with an inclined portion 11 for engaging the flange whereby the weight of the structure will operate to wedge the flange toward the wall.

As many changes could be made in the above described construction, and various embodiments of the invention could be made without departing from the scope thereof, it is intended that all matter contained in the above description, or shown in the accompanying drawing, shall be interpreted as illustrative only, and not in a limiting sense, and that the following claims are intended to cover all the generic and specific features of the invention which may be said to fall within the language of said claims.

Having thus described our invention what we claim as new and desire to secure by Letters Patent, is:

1. A bill board or the like comprising a

base portion formed of a pair of members seamed together along one edge, each of said members having a molding portion formed integrally therewith on the opposite edge, and separately formed molding pieces extending between said mentioned molding portions to complete a marginal molding about said base portion, said separately formed molding pieces being arranged to 10 bridge the seam.

2. A bill board or the like comprising a pair of separately formed members, each of said members being shaped at one edge thereof to form a marginal molding for said 15 bill board, each of said members comprising relatively flat portions extending toward each other for forming the base of the bill board, said relatively flat portions being seamed together at their adjacent 20 edges to form a stiffening rib for said base portion, and marginal molding pieces at opposite ends of the billboard between which said stiffening rib extends.

3. A bill board or the like, comprising a 25 plurality of members each having flat portions to comprise the base of the bill board, at least some of said members being bent to form molding portions along one edge thereof, and other molding portions extending 30 between said first mentioned molding portions to complete a continuous molding for the bill board, said last mentioned molding portions bridging the flat portions of said 35 plurality of members and being engaged therewith so as to reinforce and stiffen the base formed of said flat portions.

4. A bill board or the like, comprising a

plurality of members each having flat portions to comprise the base of the bill board, at least some of said members being bent 40 to form molding portions along one edge thereof, and other molding portions extending between said first mentioned molding portions to complete a continuous molding for the bill board, said last mentioned molding portions bridging the flat portions of said 45 plurality of members and being engaged therewith so as to reinforce and stiffen the base formed of said flat portions, the adjacent edges of the flat portions of 50 said plurality of members being connected together to form a reinforcing rib extending between and connecting said last mentioned molding portions and serving to reinforce the base of the bill board. 55

5. In combination, a bill board, and supporting means therefor by means of which said board is suspended upon the surface of a wall or the like, said bill board comprising a molding part extending forwardly of 60 the plane of the board and having upper and lower marginal edges connected by a flexible intermediate portion, one of the marginal edges of said molding terminating forwardly of the plane of the board, and said 65 supporting means being adapted to engage said last mentioned marginal edge.

In testimony whereof we affix our signatures in the presence of two witnesses.
